UNITED STATES PATENT OFFICE.

CHRIST. REISER, OF PRAIRIE DU CHIEN, WISCONSIN.

STEAM-BOILER CLEANER.

SPECIFICATION forming part of Letters Patent No. 247,948, dated October 4, 1881.

Application filed August 3, 1881. (No model.)

To all whom it may concern:

Be it known that I, CHRIST. REISER, a citizen of the United States, residing at Prairie du Chien, in the county of Crawford and State of Wisconsin, have invented certain new and useful Improvements in Steam-Boiler Cleaners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 shows the interior of any ordinary boiler in which my invention is placed; Fig. 2, a side elevation of my improved cleaner, parts in section; Fig. 3, view, partly in end elevation and section, of my cleaner-boiler in outline.

This invention belongs to that character of devices known as "steam-boiler cleaners;" and the novelty consists in applying a clean-out pipe to the device on which patent has already been allowed me, whereby in a very simple, cheap, easy, and quick way I am able to flush out said cleaner, and thus remove all sediment or deposit which may from time to time accumulate, and all without removing said cleaner from the boiler, all as will now be more fully set out and explained.

In the drawings, A denotes any steam-boiler, stationary or locomotive; a, its pipes or flues, and upon these flues is rested the cleaner, either directly or through the supports B. Through the inlet-pipe C, properly connecting with the water-supply, is introduced the water. This flows down the trough D into the receptacles E at each end, and thence into a central

trap or chamber, F, whence it escapes into the eduction pipes G into the boiler. This is all fully shown in my said patent, and no claim will be laid in this case on merely so much of this device.

Centrally or at one or both ends of the space or chamber F, or at any convenient point, I place a pipe and elbow attachment, H, and pipe H', which may lead out in any desired direction through the boiler-heads or boiler-shell, and be provided on the outside with a blow-off cock, I. Thus by running plenty of water through the cleaner and blowing off at the same time all the sediment or refuse matter collected from or deposited by the water in any of the chambers or traps of the cleaner will be removed. This can all be easily managed without causing the water in the boiler to foam; or the cleaner can be flushed when the boiler is cold by running plenty of water through it and opening the blow-off cock. Probably the ordinary head from any water-supply pipe will answer for this purpose; but it will be very easy to make this flow sufficiently strong to accomplish this result.

Having thus described my invention, what I consider new, and desire to secure by Letters Patent, is—

In combination with the steam-boiler cleaner composed of inlet-pipe C, trough D, receptacles E, trap F, and eduction-pipes G, the blow-off pipe H, H', suitably provided with a stop-cock, all substantially as shown and described.

In testimony whereof I affix my signature in presence of two witnesses.

CHRIST. REISER.
